UNITED STATES PATENT OFFICE.

SAMUEL MACC. JONES, OF WILKINSBURG, PENNSYLVANIA.

DESIGN FOR A SCHOOL-DESK.

47,598.

Specification for Design.

Patented July 20, 1915.

Application filed September 23, 1914. Serial No. 863,232. Term of patent 14 years.

To all whom it may concern:

Be it known that I, SAMUEL MACC. JONES, a citizen of the United States, and a resident of Wilkinsburg, in the county of Allegheny and State of Pennsylvania, have invented a new, original, and ornamental Design for School-Desks, of which the following is a specification, reference being had to the accompanying drawing, forming part thereof.

The figure is a side elevation of the school desk, showing my new design.

I claim:

The ornamental design for a school desk, as shown.

SAMUEL MACC. JONES.

Witnesses:

H. J. BOOTH,
J. B. ELLIOTT.
